UNITED STATES PATENT OFFICE.

PHILIP DENIS IONIDES, OF IPSWICH, ENGLAND, ASSIGNOR OF ONE-HALF TO RAN-
SOMES & RAPIER LIMITED, OF IPSWICH, ENGLAND, A BRITISH COMPANY.

LOCOMOTIVE HOIST AND THE LIKE.

Application filed November 17, 1924. Serial No. 750,438.

To all whom it may concern:

Be it known that I, PHILIP DENIS IONIDES, a subject of the King of England, and residing at Ipswich, in the county of Suffolk, 5 England, have invented certain new and useful Improvements in Locomotive Hoists and the Like, of which the following is a specification.

This invention relates to locomotive hoists 10 and the like and has for its object to provide an apparatus which is of simpler construction than those hitherto proposed.

According to this invention the locomotive hoist comprises vertical standards each 15 carrying a screwthreaded shaft having an independent driving element, the shaft and its driving element being so mounted upon the upper end of this standard that they can be rocked as a unit relatively to the 20 standard.

Preferably each screwthreaded shaft is provided with an independent electric motor the separate motors being connected to a common source of current having a single 25 controller for all the motors, in some cases a separate regulator being provided in the circuit of each individual motor.

Each screwthreaded shaft carries a nut 30 the nuts on each opposite pair of standards being adapted to engage a seating formed near the end of a removable transverse beam and the nut and seating being so shaped that the beam can rock relatively to the nut and quite independently of the standards which 35 do not, as hitherto, constitute guides for the beam.

Each of the standards or one pair of standards are conveniently mounted upon suitable wheels or rollers rendering them 40 mobile and capable of being moved into the correct position for the locomotive whatever the length of the latter and thus enable the standard to be employed at any place where a rigid foundation is obtainable. Further, a yielding connection is conveniently 45 provided between the wheels and the base of the standard so that the standard can automatically seat itself firmly on the ground as soon as it assumes the load.

One construction according to this invention is illustrated by way of example in the accompanying drawings, in which:—

Figure 1 is an end elevation of the complete apparatus,

Figure 2 is a diagrammatic side elevation

showing one pair of fixed and one pair of mobile standards,

Figure 3 is a side elevation of one mobile standard,

Figure 4 is a sectional elevation on an enlarged scale showing the support for the screwthreaded shaft and its driving element,

Figure 5 is a side elevation showing the upper end of the standard and the lifting beam in section, and

Figure 6 is a diagram showing the electrical connections for the four separate motors constituting a hoist.

In the construction illustrated in Figure 1, mobile standards A are adapted to support a lifting beam B by means of a screwthreaded shaft C suspended from the upper end of each standard. At the upper end of each standard an electric motor D is mounted adapted to drive the screwthreaded shaft C through a worm E and gearing E'. The motor shaft and gearing are suspended as a unit from a thrust block F which in turn is provided with a gimbal mounting. This 70 comprises a block G supported on trunnions G' provided with a V-shaped recess at right angles to the axis of the trunnions. The block F is provided with a V-shaped projection on its under side which cooperates with the V-shaped groove in the block G. The trunnions G' are supported in bearings H at the upper ends of the standard so that not only can the shaft rock within the standard to take up its required alignment but, 75 further, the screwthreaded shaft together with its driving unit can be swung clear of the standard when the lifting beam is to be inserted or removed.

Each shaft carries a nut J which supports 80 the removable lifting beam B. As will be seen from Figures 4 and 5, the nut J is provided with projecting ribs or knife edges K about which a hollow casting L is adapted to rock, the casting in turn being provided with similar knife edges L' which engage the beam B. The knife edges K and L' are so arranged that the beam B can rock relatively to the screwthreaded shafts and independently of the standards 85 which do not, as hitherto, constitute guides for this beam.

The hoist shown diagrammatically in Figure 2 comprises a pair of fixed standards A' and a pair of mobile standards A. Such 90

mobile standards are provided with wheels M and, as shown in Figure 3, a yielding connection such as springs N is provided between the wheels and the base which is capable of sustaining the weight of the standard unloaded. As soon, however, as the standard is loaded, the springs N yield and thus allow the base of the standard to seat itself firmly on the ground.

10. If, as is preferred, four separate electric motors are used connected to a common source of current, these motors may be arranged in the manner shown by the diagram in Figure 6. As will be seen from 15 this diagram, each of the four motors D is provided with a separate shunt field regulator D', D², D³ or D⁴ and limit switches O are provided in the main circuit of each individual motor so that the current will 20 automatically be cut off when the lifting beam reaches the end of its travel. The current is supplied by main leads P through a single controller Q which is conveniently 25 of the reversing type so that in normal circumstances a single operating member controls all four motors.

It is to be appreciated that the constructional details may vary considerably without departing from this invention and that 30 the particular type of self-adjusting bearing employed both between the shaft and its standard and between the beam and the nut on the shaft may be altered to suit requirements. For example, the support for 35 the shaft may be of the ball and socket type and some similar equivalent device adopted for the lifting beam.

It is to be understood that the term "locomotive hoist" used in the foregoing description and in the following claims is intended to cover any equivalent device for lifting the body or frame of a vehicle relatively to its wheels.

40 What I claim as my invention and desire to secure by Letters Patent is:—

1. In a locomotive hoist the combination of a standard, a rotatable screwthreaded shaft, a driving element for said shaft, a seating on the upper end of the standard 45 and a supporting member for the shaft and its driving element so cooperating with said seating that the shaft and its driving element can rock as a unit relatively to the standard.

2. In a locomotive hoist the combination of a standard, a yielding supporting base therefor, a rotatable screwthreaded shaft, a driving element for said shaft, a seating on the upper end of the standard and a supporting member for the shaft and its driving element so cooperating with said seating that the shaft and its driving element can rock as a unit relatively to the standard.

3. In a locomotive hoist the combination

of a mobile standard, a rotatable screwthreaded shaft, a driving element for said shaft, a seating on the upper end of the standard and a supporting member for the shaft and its driving element so cooperating with said seating that the shaft and its driving element can rock as a unit relatively to the standard.

4. In a locomotive hoist the combination of a mobile standard, supporting wheels on the base of said standard, a yielding connection between said wheels and the base of the standard, a rotatable screwthreaded shaft, a driving element for said shaft, a seating on the upper end of the standard and a supporting member for the shaft and its driving element so cooperating with said seating that the shaft and its driving element can rock as a unit relatively to the standard.

5. In a locomotive hoist the combination of a pair of standards, a rotatable screwthreaded shaft suspended from the upper end of each standard, an independent driving element for each shaft, a nut carried by each screwthreaded shaft, a transverse beam removably connected to each screwthreaded shaft and a seating near each end of the beam adapted so as to cooperate with the nut that the beam can rock relatively to the standards and relatively to each screwthreaded shaft.

6. In a locomotive hoist the combination of a pair of standards, a seating on the upper end of each standard, a rotatable screwthreaded shaft carried by each standard, an independent driving element for each shaft, a support for each shaft and its driving element so cooperating with the seating of the standard that the shaft and driving element can rock as a unit relatively to the standard, a nut carried by each screwthreaded shaft, a transverse beam removably connected to each screwthreaded shaft and a seating near each end of the beam adapted so to cooperate with the nut that the beam can rock relatively to each screwthreaded shaft.

7. In a locomotive hoist the combination of a pair of standards, a rotatable screwthreaded shaft suspended from the upper end of each standard, an independent driving element including a separate electric motor formed as a unit with each screwthreaded shaft, a source of electric current supplying both motors and a single controller therefor.

8. In a locomotive hoist the combination of a pair of standards, a seating on the upper end of each standard, a rotatable screwthreaded shaft carried by each standard, an independent driving element including a separate electric motor for each shaft, a supporting member for the shaft and its driving element cooperating with said seat-

- ing so that the shaft and its driving element can rock as a unit relatively to the standard, a source of electric current supplying both motors and a single controller therefor.
- 5 9. In a locomotive hoist the combination of a pair of standards, a rotatable screw-threaded shaft suspended from the upper end of each standard, an independent driving element including a separate electric 10 motor formed as a unit with each screw-threaded shaft, a source of electric current supplying both motors, a separate regulator in the circuit of each motor and a single controller for both motor circuits.
- 15 10. In a locomotive hoist comprising a plurality of standards including a yielding supporting base for one pair of standards, a driving element carried by each standard, a screwthreaded shaft formed as a unit with 20 each driving element and adapted to rock therewith relatively to its supporting standard, an electric motor included in each driving element, a single source of electric current for each motor, a single controller for 25 all the motor circuits, a nut carried by each screwthreaded shaft, a transverse beam removably connected to the screwthreaded shafts in each pair of standards and a seating 30 at the end of each beam adapted so to cooperate with the nuts that the beams can rock relatively to their screwthreaded shafts and independently of the standards.
- 35 11. In a locomotive hoist the combination of a plurality of pairs of standards of a driving element carried by each standard, a screwthreaded shaft formed as a unit with 40 each driving element and adapted to rock therewith relatively to its supporting standard, an electric motor included in each driving element, a single source of electric current for each motor, a single controller for 45 all the motor circuits, a separate regulator in the circuit of each motor, a nut carried by each screwthreaded shaft, a transverse beam removably connected to the screwthreaded shafts in each pair of standards
- and a seating at the end of each beam adapted so to cooperate with the nuts that the beams can rock relatively to their screw-threaded shafts and independently of the 50 standards.
12. In a locomotive hoist the combination of a standard, a gimbal-like seating on the upper end of said standard, a rotatable screwthreaded shaft, a driving element for 55 said shaft, a casing for said driving element, and a supporting member on said casing co-operating with the gimbal-like seating so that the shaft and the casing containing the driving element can rock as a single unit 60 relatively to the standard.
13. In a locomotive hoist the combination of a standard, a gimbal-like seating at the upper end of said standard, a rotatable screwthreaded shaft, an electric motor constituting a driving element for said shaft, a casing enclosing said motor, a supporting member on the casing cooperating with the gimbal-like seating so that the shaft and 65 the casing containing the driving element 70 can rock as a single unit relatively to the standard.
14. In a locomotive hoist the combination of a pair of standards, a gimbal-like seating on the upper end of each standard, a rotatable screwthreaded shaft, a driving element for said shaft, a casing for said driving element, a supporting member on said 75 casing cooperating with the gimbal-like seating so that the shaft and the casing containing the driving element can rock as a single unit relatively to its respective standard, a nut carried by each screwthreaded shaft, a transverse beam removably connected to each shaft and a seating for said 80 nuts at each end of the beam adapted to cooperate with the nuts so as to enable the beam to rock within the standards relatively to the screwthreaded shafts.
- In testimony whereof I have signed my 85 name to this specification.
- PHILIP DENIS IONIDES.
